UNITED STATES PATENT OFFICE

VERTREES YOUNG AND WALTER C. GEORGE, OF ST. LOUIS, MISSOURI, ASSIGNORS TO
ROBERT GAYLORD, INCORPORATED, OF ST. LOUIS, MISSOURI, A CORPORATION OF
MISSOURI

PACKING CASE

Application filed November 3, 1932. Serial No. 640,936.

Our invention relates to packing cases and particularly to packing cases formed of fibre board such as are adapted for use in packing meat and similar purposes.

5 The principal object of our invention is to provide improved sealing means for fastening the lid or cover of the case in closed position. Other objects of our invention are to increase the resistance of the case to crushing strain and to provide a case which may be easily handled.

In the accompanying drawings which illustrate a packing case made in accordance with our invention, Fig. 1 is a perspective view; Fig. 2 is a vertical cross section, the cover being shown in raised position; Fig. 3 is an enlarged sectional view, showing the sealing means; Fig. 4 is a view similar to Fig. 3 but showing the head of the metal seal bent outwardly, Fig. 5 is an end elevation of one corner of the case, but showing the use of a longer seal; Fig. 6 is a view similar to Fig. 3, but showing a modified form of sealing means, Figures 7 and 8 are perspective views 20 of the two clips used in the modification shown in Fig. 6; Fig. 9 is a cross sectional view showing a further modification; Fig. 10 is an enlarged sectional detail view; Fig. 11 is a top view, partly in plan and partly 25 in section taken on the line 11-11 of Fig. 9; Fig. 12 is an enlarged elevation of a portion of the front wall looking at the inner side; Fig. 13 is a view of the blank for forming 30 a modified form of cleat; and Fig. 14 is a sectional view of the cleat formed from the blank shown in Fig. 13.

The case, which is preferably made of solid fibre board, comprises front and rear walls 1 and 2, respectively, end walls 3, a top 4, and a bottom 5. The front and rear walls and bottom are formed integral and the top is preferably integral with the rear wall, as shown, so as to provide a hinged lid. The lid or cover may, however, be made separate 40 from the side walls so as to be completely removable from the case. The front and rear walls and bottom are secured to the end walls by means of flaps 6, through which pass staples 7 or for similar fastening means. 45 As shown in the drawings, the flaps 6 are car-

ried on the front and rear walls and bottom, overlapping the end walls. The reverse of this construction may be used, the flaps being carried on the end walls and overlapping the front and rear walls and bottom. We prefer, however, to use the construction shown as it permits of the use of thick and strong fibre board for the end walls, which it would be impracticable to bend over to form flaps. Secured to one or more of the side walls, 55 i. e., to the front, rear or ends, adjacent to the upper edges thereof are cleats 8. These cleats are spaced from the walls by fillers 9 so as to provide slots for the reception of flanges 10 on the cover 4.

In order to secure the cover in position, we provide one or more metal fastening clips, each comprising a barbed tang 11 and a T-head 12. The barbs on the tang extend upwardly to prevent the withdrawal of the tang after it has been forced into position. While we have shown the barbs as projecting from what may be termed the inner side of the tang so that they will engage with the side wall of the case, they may project from the 70 opposite side so as to engage with the filler. As shown in Figures 1 to 5, inclusive, slits 13 are formed at the junction of the flanges 10 and the top. These slits are of such length as to permit the passage of the tang of the 75 clip but to prevent the passage of its head.

In using the sealing device, the lid is first closed and then the shanks of the fastening strips are passed down through the slits 13 and forced between the side wall of the case 80 and the filler. The barbs prevent the fastening strip from being pulled out so that the lid is securely firmly in position. The head may be either bent inwardly, as shown in Fig. 3, or outwardly, as shown in Fig. 4, 85 and the bending may be done either before or after the insertion of the clip. To open the case it is necessary to remove the head by breaking or cutting it from the tang. To facilitate this operation and to prevent the 90 formation of sharp corners on the remaining tang, we prefer to form notches at the junction of the head and tang, as shown in Fig. 8.

When the length of the tang is less than the widths of the cleat, the tang cannot be 100

withdrawn after the head is removed and resealing is thus prevented. In case it is desired to reseal the case after it has been opened, clips are used, the tangs of which are somewhat longer than the width of the cleats, so that the ends will project, as shown in Fig. 5. After the removal of the heads, these projecting ends may be engaged by a suitable tool and withdrawn as the barbs will not prevent the movement of the tangs in a downward direction.

In Fig. 6, we have shown a modification in which the slits for the passage of the tang of the fastening clip are not formed in the lid but in an auxiliary clip movable with the lid. This auxiliary clip, shown in detail in Fig. 7, comprises inner and outer plates 15 and 16, respectively, and a connecting web 17 in the latter of which is formed a slit 18 for the passage of the tang 11. Formed on the plate 15 are downwardly projecting barbs for engagement with the flange 10.

In using the form of fastening illustrated in Fig. 6, the auxiliary clip is placed astride the upper edge of the cleat before the lid is closed. When the lid is closed, the flange 10 engages with the barbs on the auxiliary clip so that the lid cannot be raised without withdrawing the auxiliary clip along with it. The main clip is now inserted as previously described except that its tang is passed through the slit 18 in the auxiliary clip instead of through the lid itself. In this construction the tang enters between the cleat and the filler instead of between the filler and the side wall. The barbs as shown engage with the filler. They may, however, project from the opposite side so as to engage with the cleat, as the same result is secured in either way.

It is to be noted that in our construction, the upper edge of the end wall, which may be made of any desired thickness, abuts directly against the cover without any intervening bend, thus adding to the resistance of the case to crushing strain. The upper edge of the front wall is, however, preferably provided with an inwardly projecting flap 19 to overlap the cover, and so provide a better joint with the latter.

This flap 19 may, however, be omitted in case the flange and the front edge of the cover is made to extend the entire length of the case.

55 In addition to forming part of the fastening means for the lid, the cleats on the ends 3 provide handles by means of which the case may be conveniently lifted. If heavy fibre board is used for the cleats and filler to provide an effective handle, difficulty may be encountered in inserting the staples 7 through the three sheets of material. In order to provide a handle of sufficient thickness without the use of unduly heavy material, we may use the construction shown in

Figs. 13 and 14 in which a cleat 8' and a filler 9' are formed integral, the filler being folded to overlap the cleat. As the fibre board is quite stiff, the fold will not be perfectly flat but will assume the form of a more or less open loop, as shown in Fig. 14, thus substantially increasing the thickness of the handle.

In Figs. 9 to 12, we have shown a modification in which means is provided for strengthening the front and rear walls of the case at their middle points and at the same time, obviating the use of a projecting cleat on the outer face of the front wall. In this construction an opening 21 is formed between the front wall and the flap 19 to permit the passage of the flange 10 on the front edge of the cover. Positioned against the inner face of the front wall is a sheet of fibre board 22, having formed in its upper end a recess 23 for the reception of the flap 10 on the front edge of the cover. Over the sheet 22 is placed a sheet 24 and both sheets are secured in position by staples or by any other suitable means. The sheets 22 and 24 perform the same function as the cleat and filler heretofore described and at the same time form a vertical strut or brace extending between the bottom and cover at the center of the length of the case. A strut or brace 25 is secured to center of the inner face of the rear wall 2. This strut may be formed of a single heavy sheet of fibre board.

Having fully described our invention, what we claim as new and desire to secure by Letters Patent of the United States is:

1. A packing case comprising a body and a cover, said body having a cleat secured to a side wall thereof, said cover having a flange extending between the wall and cleat, and a sealing device insertable at one side of the flange and anchored below the lower edge thereof to hold the cover in closed position.

2. A packing case comprising a body and a cover, said body having a cleat secured to a side wall thereof, said cover having a flange extending between the cleat and wall, a clip inserted between the cleat and wall, said clip being barbed to prevent its withdrawal, and a head carried by said clip for holding the cover in closed position.

3. A packing case comprising a body and a cover, a cleat secured to one of the side walls of the body, a filler spacing said cleat from the wall, a flange carried by said cover and adapted to enter the space between the wall and cleat, a clip insertable between the cleat and wall at one side of said flange, said clip extending below the flange at one side of the filler and being barbed to prevent its withdrawal, and a head on said clip for holding the cover in closed position.

4. A packing case comprising a body and a cover, said body having a cleat secured to a side wall thereof, said cover having a flange

adapted to extend between the cleat and wall, a slit formed at the junction of the cover and flange, a clip insertable through said slit between the flange and wall, said clip being
 5 barbed to prevent its withdrawal, and a head on said clip for holding the cover in closed position.

5. A packing case comprising a body and cover, a cleat secured to one of the side walls
 10 of the body, a filler spacing the cleat from the wall, a flange carried by said cover, a slit formed at the junction of the cover and flange, a clip insertable through said slit at the inner side of the flange, said clip extending
 15 below the flange at one side of the filler and being barbed to prevent its withdrawal, and a head on said clip for holding the cover in closed position.

6. A packing case comprising a body and cover, a cleat secured to one of the side walls of the case, a flange carried by the cover and adapted to extend between the cleat and wall, a clip provided with a slit, said clip being barbed to engage with said flange, and a second
 25 clip having a barbed tang adapted to pass through the slit in the first named clip, and a head for preventing the disengagement of the clips.

7. A packing case comprising a body and cover, a cleat secured to one of the side walls of the body, a filler spacing the cleat from the wall, a flange carried by said cover and adapted to enter the space between the wall and cleat, a clip adapted to be inserted between the flange and cleat, said clip being
 35 provided with a slit and barbed to engage with the flange, and a second clip having a barbed tang for insertion through said slit, and a head for preventing disengagement of
 40 the clips, said tang extending below the flange between the filler and cleat.

8. A packing case comprising a body and a cover, said cover being provided with a flange, a side wall of the body being provided
 45 with an inturned flap, an opening in said flap for the passage of said flange, a strut positioned against the inner face of said side wall, said strut being provided with a recess for the reception of the flange, and fastening
 50 means for holding the cover in closed position.

In testimony whereof, we hereunto affix our signatures, this 31st day of October 1932.
